UNITED STATES PATENT OFFICE.

LAURA BASSETT, OF PRINCETON, MINNESOTA.

DESIGN FOR A PASTRY-MIXER.

SPECIFICATION forming part of Design No. 33,073, dated August 14, 1900.

Application filed July 17, 1900. Serial No. 23,980. Term of patent 7 years.

To all whom it may concern:

Be it known that I, LAURA BASSETT, a citizen of the United States, residing at Princeton, Mille Lacs county, Minnesota, have invented and produced a new and original Design for a Pastry-Mixer, of which the following is a specification, reference being had to the accompanying drawings, forming part thereof.

Figure 1 is a perspective view of a cake-stirrer. Fig. 2 is a side view. Fig. 3 is a top or plan view of the article.

As shown in the accompanying drawings, the leading or material feature of my design consists of the handle A, having rounded or curled edges B and united at its lower end at an obtuse angle to the body or blade portion C. The body portion C and the handle A are of substantially the same width at their point of union, and near this point in the body portion is a transverse slot or opening

D. The part C is flat on both faces and is divided into a series of wide tines or prongs E by slits or slots F, that extend up into the body portion to a point near the slot D. The slits F are of substantially the same width as the tines E, and said tines are of substantially the same length, each being square at its end and diverging slightly, so that at the outer end of the tines the body portion C is considerably wider than at its point of union with the handle A.

I claim as my invention—

The design for a pastry-mixer, substantially as shown and described.

In witness whereof I have hereunto set my hand this 12th day of May, 1900.

LAURA BASSETT.

In presence of—

E. D. CLAGGETT,
E. MARK.
